DESIGN FOR A SHOE

Abraham Turiansky, New York, N. Y.

Application November 5, 1936, Serial No. 65,712

Term of patent 3½ years

To all whom it may concern:

Be it known that I, Abraham Turiansky, a citizen of the United States of America, residing in city of New York, county of New York, and State of New York, have invented a new, original, and ornamental Design for a Shoe, of which the following is a specification, reference being had to the accompanying drawing, forming part thereof,

Fig. 1 is a plan view of a shoe showing my new design.

Fig. 2 is a side elevational view of a shoe as shown in Fig. 1.

I claim:

The ornamental design for a shoe substantially as shown.

ABRAHAM TURIANSKY.
